UNITED STATES PATENT OFFICE.

OLIVER S. SLEEPER, OF BUFFALO, NEW YORK, ASSIGNOR TO BUFFALO FOUNDRY AND MACHINE COMPANY, OF BUFFALO, NEW YORK, A CORPORATION OF NEW YORK.

VACUUM DRYING APPARATUS.

1,073,872.

Specification of Letters Patent. Patented Sept. 23, 1913.

Application filed February 14, 1908, Serial No. 415,798. Renewed May 10, 1913. Serial No. 766,891.

To all whom it may concern:

Be it known that I, OLIVER S. SLEEPER, a citizen of the United States, residing at Buffalo, in the county of Erie and State of New York, have invented a new and useful Improvement in Vacuum Drying Apparatus, of which the following is a specification.

This invention relates to a continuous vacuum drier and has the object to produce an improved machine of the character whereby a liquid solution may be dried thoroughly and economically and with a minimum expenditure of heat, labor and power and which can be thoroughly and easily cleaned.

In the accompanying drawings consisting of 5 sheets: Figure 1 is a side elevation of my improved continuous vacuum drier. Fig. 2 is an end elevation of the same. Fig. 20 3 is a vertical cross section in line 3—3, Fig. 1. Fig. 4 is a vertical longitudinal section taken in line 4—4, Fig. 3. Fig. 5 is a horizontal section taken in line 5—5, Fig. 3. Fig. 6 is a fragmentary vertical transverse 25 section, on an enlarged scale, in line 6—6, Fig. 4. Fig. 7 is a fragmentary vertical transverse section in line 7—7, Fig. 4, on an enlarged scale. Fig. 8 is a fragmentary top plan view, on an enlarged scale, of one form 30 of my improved means of delivering the solution to be dried to the heating drum. Fig. 9 is a fragmentary vertical longitudinal section showing a modification of the means for agitating the solution to be dried and 35 delivering the same to the heating drum. Fig. 10 is a fragmentary vertical cross section of the same in line 10—10, Fig. 9.

Similar letters of reference indicate corresponding parts throughout the several 40 views.

Referring to Figs. 1—8, A represents the vacuum or drying chamber which is constructed generally in the form of a horizontal cylinder the upper part of which is circular while the lower part thereof is constructed in the form of a longitudinal trough the side walls a , a of which converge downwardly. This chamber may be supported by any suitable means but preferably by a frame having standards a^1 as shown in the drawings. Lengthwise within the vacuum chamber is arranged a horizontal hollow heating drum B which rotates vertically in

the direction of the arrow in Fig. 3 and is journaled by means of hollow trunnions b , b^1 55 which project outwardly from the heads at opposite ends of the drum and turn in bearings b^2 , b^3 formed in the heads at opposite ends of the vacuum chamber. The rotation of this cylinder may be effected by any suitable means. For the purpose of heating the drum a heating medium, preferably steam, is conducted into the interior of the drum, this being preferably effected by means of a stationary supply pipe C arranged concentrically within the hollow front trunnion b of the drum and supported by a bracket D on the front head of the vacuum chamber, a stuffing box d being interposed between this steam supply pipe and the front trunnion 60 for maintaining a steam tight joint between these parts. The water of condensation is removed from the interior of the heating drum by means of a stationary outlet pipe E arranged concentrically within the hollow rear trunnion and supported by a bracket e on the rear head of the vacuum chamber, a stuffing box e^1 arranged between the outlet pipe and the rear trunnion for producing a steam tight joint between these parts, an 65 oblique scoop F arranged lengthwise on the inner side of the heating drum with its front end in advance of its rear end, and an intermediate pipe f connected at its outer end with the rear receding end of the scoop and 70 connected at its inner end with the rear trunnion b^1 and curved in a direction opposite to that in which the heating drum rotates. During each rotation of the drum any water of condensation which gathers 75 within the lower part of the same is caught by the scoop and as the latter rises, this water is caused to flow from the front end to the rear end of the scoop owing to the inclination thereof and is then carried by 80 the intermediate pipe from the rear end of the scoop into the discharge pipe. 85

Below the heating drum is arranged the nozzle whereby the solution to be dried is delivered to the underside of the heating 90 drum. This nozzle comprises a hollow tubular body or pipe G arranged lengthwise below the heating drum and provided with a longitudinal outlet slot or throat g which is normally on the upper side of the body and 95 faces the periphery of the heating drum, a 100 faces the periphery of the heating drum, a 105

wide delivery or distributing plate shelf H arranged on the tubular body in front of its slot and extending practically the full length of the drum, a baffle plate I arranged on the 5 tubular body in rear of its slot, a rib i arranged on the upper side of the baffle plate, and guard ribs or flanges j arranged transversely on the upper side of the distributing shelf at opposite ends thereof. The body of the nozzle 10 extends at its front and rear ends through stuffing boxes g¹, g² on the front and rear heads of the vacuum chamber which stuffing boxes form bearings in which the nozzle may turn for convenience in cleaning the solution 15 delivery device. In the operative position of the nozzle its front shelf is arranged concentrically with the heating drum, as shown in Figs. 3 and 7, and is separated by an intervening space from the periphery of the 20 heating drum. The baffle plate I is separated from the distributing plate by a narrow intervening slit h and its rib i extends nearer to the periphery of the heating drum than the distributing plate, thereby forming 25 a dam which prevents the solution from flowing backwardly from the nozzle.

The guard ribs j prevent the solution from escaping at the ends of the distributing plate or shelf and reaching the end heads of the 30 drum which cannot be readily cleaned or scraped. The several parts of the delivery nozzle thus produce a basin or tray the upper concave side of which faces the periphery of the drum and forms with the latter a narrow 35 passage way or intervening space. The solution to be dried passes from the tubular body upwardly through its outlet slot and through the slit between the baffle plate and distributing plate, and thence forwardly in 40 the form of a shallow stream between the upper side of the distributing plate and the underside of the heating drum. The solution at this time is prevented from passing backwardly over the delivery nozzle owing 45 to the dam on the rear part of the nozzle which is higher and extends closer to the periphery of the heating drum than the distributing plate. As the drum rotates forwardly in contact with the stream of solution 50 flowing in the same direction over the distributing plate, a thin film of this solution adheres to the drum, this deposit of the solution on the drum proceeding continuously while the machine is in operation. The 55 surplus solution which is not picked up by the drum flows downwardly over the front edge of the distributing plate or shelf and drops upon the trough-shaped bottom of the vacuum chamber below the delivery nozzle. 60 The film of solution adhering to the heating drum is carried upwardly on the front side of the drum and downwardly on the rear side thereof during which time all moisture contained therein is evaporated owing to the 65 heat of the drum, leaving only the dried resi-

due or material adhering to the drum. This dried material is continuously removed from the drum before the respective part of the drum reaches the solution feeding device which will be hereinafter described.

While the machine is in operation the working of the delivery nozzle may be observed from the exterior by windows J arranged in the end heads of the vacuum chamber, as shown in Figs. 2, 3 and 6.

The solution to be dried is preferably supplied to the nozzle under pressure by a feed device which may be connected with either end of the nozzle body while the other end is closed. As shown in Fig. 1, the solution delivery pipe K is connected by a rotatable joint k with the front end of the nozzle body while the rear end of the same is closed by a cover k¹. The means for delivering the solution under pressure shown in Fig. 1 80 consists of a pump L which has its outlet connected with the delivery pipe K. If desired, the supply may be derived from an elevated tank in which case gravity alone would furnish the required pressure. When 85 it is desired to clean the delivery nozzle the same is turned downwardly from the position shown in full lines in Fig. 7 to the position shown by dotted lines in the same figure, whereby access may be had to all of 90 its parts for thoroughly cleaning the same. While the nozzle is thus turned downwardly for cleaning purposes access may be had to the same through man-holes in the lower part of the vacuum chamber which are 95 normally closed by covers K². The rotation of the solution delivering or distributing device into and out of its operative position may be effected by various means, those shown in Figs. 1, 2, 4 and 6 of the drawings 100 105 being suitable for this purpose and consisting of a gear segment M secured to the front end of the nozzle body, a worm m engaging with the gear segment, a shaft m¹ journaled in bearings on the front head of the vacuum chamber and carrying the worm, and a crank m² applied to said shaft for turning the same.

The surplus solution which escapes over the front edge of the distributing plate and 115 drops upon the trough-shaped bottom of the vacuum chamber below the same is conducted into a receiver or storage reservoir N by one or more return pipes n. This reservoir is preferably constructed in the 120 form of a horizontal cylinder which is arranged lengthwise below the vacuum chamber and the pipes n connect the lowermost part of the trough or bottom of the vacuum chamber with the top of the reservoir. Within this reservoir is arranged a 125 stirrer or agitator which operates to mix the solution contained therein and prevents the solids thereof from settling or precipitating. This agitator may be of any 130

suitable construction that shown in Figs. 3 and 4 being preferred and consisting of a horizontal shaft O arranged lengthwise in the lower part of the reservoir and journaled at its opposite ends in stuffing box bearings o, o¹ in the front and rear heads of the reservoir and two longitudinal dashers, beaters or blades o² arranged lengthwise on opposite sides of the agitator shaft and connected therewith by transverse arms o³. Upon rotating the agitator its blades move close to the lower part of the reservoir or receiver and stir up any solids which have a tendency to settle, thereby maintaining the solution of uniform consistency and in the best condition for delivery to the heating drum and its evaporation thereon. The agitator may be driven in any suitable manner, the gear wheel p mounted on the front end of the agitator shaft being the only part of the driving mechanism which is represented in the drawing. Arranged lengthwise on the inner side of the reservoir on opposite sides of the agitator are two baffle plates or flanges q which intercept the solution upon being moved by the agitator, thereby breaking up the solution and causing the same to be thoroughly mixed. For the purpose of permitting the condition of the solution in the reservoir and the operation of the agitator to be observed from the exterior, windows J¹ are placed in the heads at the ends of the reservoir, as shown in Figs. 2, 3 and 4. On its underside the reservoir is connected with the supply pipe R leading to the inlet of the pump, whereby the latter when in operation withdraws the solution from the reservoir and delivers the same against the underside of the heating drum by means of the nozzle. It will thus be noted that by this means a constant circulation of the solution is maintained. The quantity of solution is however gradually reduced by reason of the heating drum picking up a continuous film of the same in passing with its lower part in contact with the top of the stream flowing over the distributing plate. When the quantity of solution in circulation has diminished below the normal the same may be replenished by introducing an additional quantity into the reservoir through one or more openings in the top thereof which are normally closed by caps or covers r. The means shown in the drawings for removing the dried residue from the heating drum and discharging the same from the machine are constructed as follows: S represents a horizontal conveyer trough arranged lengthwise on the rear side of the vacuum chamber and provided at opposite ends with downwardly projecting discharge nipples, s, s. Within this conveyer trough is arranged a rotatable screw conveyer T one end of which is adapted to be connected with means

for driving the same. t represents a scraper knife or blade which engages with the periphery of the heating drum between the conveyer trough and the return hopper of the vacuum chamber and which is adapted to remove the dried residue from the heating drum and direct the same into the conveyer trough. The material thus removed from the heating drum and delivered into the trough is propelled by the conveyer and discharged through one of the delivery nipples. The material may be discharged through either one or the other of these nipples according to the position of the machine in the plant or other condition, the particular nipple not in use being closed by a cover t¹ and the conveyer being rotated in the proper direction for propelling the material to the delivery nipple which is in use. Any suitable trap valve may be employed in connection with the delivery nozzle which is in use to permit the dried material to be discharged from the machine but prevent the entrance of the external atmosphere into the vacuum chamber.

The scraper t or blade is pivotally supported at its lower end on the vacuum chamber so that the scraper can be moved toward and from the heating drum and means are provided for yieldingly holding the plate in engagement with the heating drum when the machine is in operation which means are constructed to permit not only of regulating the pressure of this scraper against the drum but also permit of moving the blade away from the drum when required.

To permit of observing the operation of the scraper and conveyer one or more windows t² are arranged on the rear side of the vacuum chamber above the conveyer which windows are capable of being cleaned by means of a wiper t³ capable of being operated from the exterior of the vacuum chamber.

The drying of the material on the heating drum is facilitated by connecting the vacuum chamber with a condenser, vacuum pump or other exhausting device whereby the vapors are forcibly withdrawn from the vacuum chamber. The vapors escape through four vapor outlet nipples U arranged on the upper front part of the vacuum chamber. Instead of leading the vapors from the vacuum chamber directly to the exhausting device, means are interposed between the vacuum chamber and said exhausting device for intercepting any dust or fine particles of the dried material which may be floating in the vacuum chamber. The means for this purpose shown in the drawings are constructed as follows: V, V represent two separating chambers arranged on the front side of the vacuum chamber and each connected centrally on its upper side by a

vapor pipe v with a condenser, vacuum pump or other exhausting device not shown in the drawings. Extending downwardly into each separating chamber on opposite sides of its vapor pipe are two separating pipes W which are connected at their upper ends with corresponding vapor outlet nipples U of the vacuum chamber while their lower ends terminate above the bottom of the separating chamber and are provided with serrations or notches w . Each of the separating chambers is filled with liquid, preferably water, to a point above the lower end of the separating pipe the level of which may be determined by means of gages X applied to said chamber. When the exhausting device connected with the vapor pipes is working, the vapors drawn from the vacuum chamber pass through the nipples U , thence downwardly through the pipes W , thence upwardly through the separating chamber and thence outwardly through the main vapor pipes. As the vapors pass upwardly from the separating pipes through the separating chambers to the vapor outlet pipes the same move through the body of water in the separating chamber, whereby some of the vapors are condensed and any dust or light dried residue which has been drawn over from the vacuum chamber is taken up by the water and separated from the vapors, thereby saving the same. By serrating the lower edges of the separating pipes, the vapors in passing around the lower edge of the same are disintegrated or broken up, thereby insuring thorough separation therefrom of the light particles of dried material and preventing the same from escaping with the vapors as would be liable to occur if the lower edge of the separating pipes were straight and permitted the vapors to pass around the same in the form of large bubbles. When the separating water in the separating chambers becomes heavily loaded with dust particles, the same may be withdrawn through discharge pipes x^1 having valves x^2 and returned to the reservoir to be again subjected to the vacuum drying operation hereinbefore described. Access to the interior of each separating chamber for cleaning and inspection may be had through a manhole in its side which is normally closed by a cover w^1 , as shown in Figs. 1 and 2.

Instead of distributing or delivering the solution to the drum and agitating the same by the means shown in Figs. 1-7, this may be effected by the modified means which are shown in Figs. 9 and 10 and which are constructed as follows: Y represents the tubular body of a delivery nozzle arranged lengthwise below the heating drum and having a longitudinal slot Y^1 in its upper side and supported in the end walls of the vacuum chamber. In its upper side the delivery nozzle

or pipe is provided with two longitudinal upwardly diverging side walls y , y and two end walls y^1 , y^1 . The lower edges of the side walls are separated by an intervening longitudinal slit whereby the tubular body communicates with the basin or space between the walls y , y^1 . The upper ends of the side walls y are separated from the periphery of the heating drum by an intervening space, as shown in Fig. 10. Each of the end walls is provided with a guard rib or packing strip y^2 which engages with the periphery of the heating drum and prevents the liquid from flowing over the ends of the basin. The solution passes from the tubular body Y upwardly through the slit in the bottom of the basin and after filling the latter overflows opposite longitudinal edges thereof. The heating drum rotates with its periphery in contact with the flowing body of solution in the basin and picks up a thin film of the same which is dried thereon and subsequently removed. The surplus of the stream falls from opposite edges of the trough and is returned to the reservoir to be again circulated in the manner hereinbefore described.

In order to prevent the solution from settling in the delivery basin an agitator is located therein which preferably consists of a longitudinally reciprocating bar Z arranged lengthwise in the basin and extending at one end through the basin and nozzle body to the exterior of the machine and a plurality of triangular wings, blades or flights z^1 secured transversely to the longitudinal bar. The means for reciprocating this agitator shown in Fig. 9 of the drawings consists of a yoke z^2 secured to the end of the bar Z , and a rotating crank z^3 provided with a slide z^4 movable transversely in said yoke.

In the use of this machine the total amount of solution which is in circulation in the machine does not exceed an amount which would fill the reservoir up to its filling openings. By this means the entire batch of solution can be held in the reservoir, thereby avoiding accumulating any of the solution in the lower part of the vacuum chamber and preventing any solution from over-flowing from the latter into the conveyor trough containing the dried material.

I claim as my invention:

1. A vacuum drying apparatus comprising a vacuum chamber, a delivery pan independent of the bottom of said chamber arranged in the lower part of the vacuum chamber and adapted to support a stream of the condensate, a heating drum rotatable within the upper part of the vacuum chamber and adapted to dip its lower part into the condensate within said pan, means for supplying said pan with condensate in excess of the amount which the drum is able to carry away and thereby cause the excess con-

densate to flow over the edge of the pan, and a catch basin communicating with the lower part of the vacuum chamber and adapted to receive the surplus condensate escaping from 5 said delivery pan.

2. A vacuum drying apparatus comprising a vacuum chamber, a horizontal heating drum rotating vertically within said chamber, and a nozzle for delivering the solution 10 to the periphery of the drum having a tubular body arranged lengthwise below the drum and provided with a longitudinal delivery slot on its upper side, a distributing shelf separated from the periphery of the 15 drum by an intervening space and arranged on said body in front of its slot, and a dam arranged on said body in rear of its slot and extending closer to the periphery of the drum than said shelf, substantially as set 20 forth.

3. A vacuum drying apparatus comprising a vacuum chamber, a horizontal heating drum rotating vertically within said chamber, and a nozzle for delivering the solution 25 to the periphery of the drum having a tubular body arranged lengthwise below the drum and provided with a longitudinal delivery slot on its upper side, a distributing shelf separated from the periphery of the 30 drum by an intervening space and arranged on said body in front of its slot, a dam arranged on said body in rear of its slot and extending closer to the periphery of the drum than said shelf, and guard flanges arranged 35 transversely at opposite ends of said shelf and engaging the periphery of the drum, substantially as set forth.

4. A vacuum drying apparatus comprising a vacuum chamber, a horizontal heating 40 drum rotating vertically within said chamber, and a movable solution delivery nozzle arranged adjacent to the underside of the periphery of the drum and capable of being moved with its outlet toward the drum for 45 delivering the solution to the drum or with its outlet away from the drum to permit of cleaning the nozzle, substantially as set forth.

5. A vacuum drying apparatus comprising 50 a vacuum chamber, a horizontal heating drum rotating vertically within said chamber, and a nozzle arranged below the drum and adapted to deliver the solution to the underside of the periphery of the drum having a rotatable tubular body provided 55 with an outlet adapted to face either toward or away from the periphery of said drum, substantially as set forth.

6. A vacuum drying apparatus comprising 60 a vacuum chamber, a horizontal heating drum rotating vertically within said chamber, a nozzle for delivering the solution to the periphery of the drum having a rotatable tubular body provided with an outlet 65 adapted to face either toward or away from

the periphery of said drum and means for turning said body comprising a worm segment secured to the body, a shaft, a worm arranged on the shaft and meshing with said segment, and a crank arranged on said shaft, 70 substantially as set forth.

7. A vacuum drying apparatus comprising a vacuum chamber, a rotatable heating drum arranged in the upper part of said chamber, a delivery pan independent of the 75 bottom of said chamber arranged below the drum and adapted to support a stream of condensate against the underside of the drum, a pump for supplying said pan with condensate in excess of the quantity which 80 can be carried away by said drum, and a catch basin arranged below said pan and receiving the surplus condensate from said pan and supplying the same to said pump for returning the condensate to said pan. 85

8. A vacuum drying apparatus comprising a vacuum chamber, a heating drum arranged in said chamber, a nozzle arranged in said chamber and adapted to deliver a stream of solution so that the drum will 90 pick up a film thereof while the surplus drops to the bottom of the chamber, and a reservoir connected with the lowest part of said chamber and adapted to receive the surplus solution therefrom and an agitator 95 arranged in said reservoir, substantially as set forth.

9. A vacuum drying apparatus comprising a vacuum chamber, a heating drum arranged in said chamber, a nozzle arranged 100 in said chamber and adapted to deliver a stream of solution so that the drum will pick up a film thereof while the surplus drops to the bottom of the chamber, a reservoir connected with the lowest part of said chamber and adapted to receive the surplus solution therefrom, and an agitator arranged in 105 said reservoir and comprising a shaft, blades mounted on the shaft, and baffle plates arranged on the inner side of the reservoir 110 adjacent to the path of said blades, substantially as set forth.

10. A vacuum drying apparatus comprising a vacuum chamber, a vertically rotating drum arranged in said chamber, and means 115 for applying the solution to be dried to said drum comprising a nozzle which is arranged below the drum and supports a stream of solution in contact with the underside of the drum and which terminates at its opposite ends short of the ends of the drum. 120

11. A vacuum drying apparatus comprising a vacuum chamber, a vertically rotating drum arranged in said chamber, and means for applying the solution to be dried to said 125 drum comprising a nozzle which is arranged below the drum and supports a stream of solution in contact with the underside of the drum and which terminates at its opposite ends short of the ends of the drum and 130

transverse flanges arranged at opposite ends of the pan and projecting toward the periphery of the drum.

12. A vacuum drying apparatus comprising a vacuum chamber, a rotatable heating drum arranged in said chamber and having hollow trunnions journaled in bearings on the same, a stationary steam inlet pipe arranged in one of the trunnions, a stationary outlet pipe arranged in the other trunnion, a scoop arranged obliquely on the inner side of the drum with its front end in advance of its rear end, and an intermediate pipe connecting the rear end of the scoop with the outlet pipe, substantially as set forth.
13. A vacuum drying apparatus comprising a vacuum chamber, a rotatable heating

drum arranged in said chamber, a delivery pan independent of the bottom of said chamber which is arranged below the drum 20 and which is adapted to support a body of condensate against the under side of the drum and from which the excess condensate which is not picked up by the drum is discharged into the lower part of said chamber, and means for withdrawing the condensate from the bottom of the vacuum chamber and delivering the same to said pan. 25

Witness my hand this 11th day of February, 1908.
